UNITED STATES PATENT OFFICE.

CHARLES H. BROWN, OF FLUSHING, NEW YORK.

SHOE LAST.

Application filed April 11, 1925. Serial No. 22,252.

Among the principal objects which the present invention has in view are: to accommodate an insole for shoes for personal wear being molded and set to form an elevated area inside the shoe to be constructed in the region of the metatarsal arch of the human foot; to provide a last as characterized with a recess for receiving an upstanding molded portion shaped in correspondence with the under surface of the human foot and particularly that portion of the human foot where the metatarsal arch is located.

Drawings.

15 Figure 1 is a side view of a last as characterized constructed and arranged in accordance with the present invention, a portion of the last being cut away to show the longitudinal sectional shape of the recess for 20 receiving the pad, the section being cut as on the line 1—1 in Fig. 2.

Figure 2 is a view of the under side of the last.

Figure 3 is a cross section of the last on 25 enlarged scale, the section being taken as on the line 3—3 in Figure 2.

Description.

Heretofore, shoes have been constructed 30 wherein there has been provided a thickened area or a padded portion in the region of the metatarsal arch of the human foot. This padded portion usually has been constructed by placing a pad between the inner and 35 wearing soles of the shoe relying upon the unequal resistances of the insole and foundation thereof to provide special support for the metatarsal arch. This has proved both unsatisfactory and inefficient owing to several reasons, among them being that the pad 40 thus provided would become displaced with consequent discomfort to the wearer of the shoe, and again, if the insole is constructed of substantial leather, it will resist the pressure over the whole area and thus avoid 45 special pressure in the region of the metatarsal arch. These difficulties are overcome in the present invention by providing a recess 8 which is cut into the body of the 50 last and in the sole portion 9 thereof. The recess referred to is adjacent the shank portion 10 of the last, the rear walls 11 of the recess being substantially vertical and disposed coincident with the forward terminal 55 end of the shank portion 10. The recess is preferably shaped as shown in the drawings,

the forward edge 12 fading into the sole portion 9 of the last.

From the forward edge 12 the recess rises or is deepened in the last back, to the rear 60 walls 11. The recess thus formed is intended to house a raised or molded portion of a relatively thickened insole such as disclosed in an application for patent for improvement in "shoe insole" filed by me under 65 date of April 22, 1924, having Serial No. 708,236, to which application, cross reference is here made, the thickened portion of the insole referred to being indicated in the drawings of the said application by means of 70 the numeral 19. The wall 11 of the recess 8 in the present invention is shaped to correspond with the molded portion 19 of the application above referred to.

A shoe last thus constructed is used in the manufacture of shoes first receiving the insole, the molded portion of the insole fitting a recess 8 of the last. A shank iron having an upset forward extension corresponding to 75 the molded portion of the insole and of the recess 8 is then placed upon the insole, the upset portion resting in the concave side of the molded portion of the insole. When the shoe is completed and the last is removed therefrom it is easily drawn back over the 80 raised portion of the insole, the inclined upper surface corresponding with the recess 8 affording ease with which the last may be drawn back. It will now be found that the shoe is provided with a substantially 85 lifted or elevated area which registers with the foot of the wearer and under the metatarsal arch thereof to support the same 90 in service.

The present disclosure differentiates from the disclosure shown in a Patent No. 1,237,464 granted to me August 21, 1917, for improvements in "lasts" in that the recess 8 is deepest at what may be termed the rear 95 of the wearing sole of the shoe, whereas in the former disclosure the recess was deepest at the forward edge thereof or what may be termed within the wearing sole of the shoe. In the former disclosure, the recess was intended to receive a pad that was supported by a forward extension of the shank iron of the shoe and the thickest dimension of the pad was coincident with the forward edge of the recess. In the present disclosure the recess 8 is designed to receive the upset portion 100 of the molded insole which supplements or replaces the pad above referred to as pro-

vided for in the older construction and at the same time affords a registering member for locating the insole on the last during the process of manufacturing shoes.

5 I claim:

A shoe last having a cavity on the sole portion thereof adjacent the forward end of

the shank portion thereof, the deepest portion of said cavity being adjacent the parting line of said sole and shank portion of the last, the lines of the rear walls of said cavity being coincident with the juncture of said sole portion and said shank portion. 10

CHARLES H. BROWN.
